Application January 26, 1942, Serial No. 428,216

10 Claims.

(Cl. 308—6)

This invention relates to machines with reciprocating carriages or slides and in particular to guideway constructions for such carriages.

One object of this invention is to provide a carriage or slide guideway construction wherein the carriage is automatically urged against its guideway by resilient devices.

Another object is to provide a self-adjusting machine way construction wherein the carriage or slide reciprocates along guideways with flat surfaces, the carriage or slide being urged constantly into engagement with the guideways by spring urged plungers, these preferably having rollers for engaging the guideways.

In the drawing:

Figure 1 is a diagrammatical side elevation of a machine having reciprocating slides or carriages embodying the self-adjusting guideway construction according to the present invention;

Figure 2 is a top plan view of the left-hand end of Figure 1;

Figure 3 is a vertical cross-section along the line 3—3 in Figure 1;

Figure 4 is a horizontal section along the line 4—4 in Figure 1;

Figure 5 is a front elevation of the structure shown in Figure 4.

General arrangement.

In general, the invention consists of a self-adjusting guideway construction for machines having reciprocating slides or carriages. The bed of the machine is provided with hardened steel ways or guide rails with accurately machined side and top surfaces. These are engaged by correspondingly machined surfaces upon the bottom and inner side walls of the carriage or slide, which is provided with downwardly extending flanges along its edges. Mounted in one of these flanges are hollow plungers having rollers mounted on their outer ends. These rollers are urged into engagement with the side wall of one of the guide rails or ways by coil springs mounted within the hollow plungers and seated against plugs held in brackets secured to the slide or carriage. In this manner the corresponding surfaces of the slide and guideways are urged constantly into sliding engagement with one another so that any wear is automatically taken up.

The invention is especially well adapted to the construction of machine tools having reciprocating carriages. Hitherto in machine tools, such as lathes, shapers, grinders, milling machines, planers, and the like, it has been difficult to maintain a free sliding engagement between the slides

or carriages and the machine bed, and at the same time to retain high precision and accuracy in the operation of the machine. The present invention has been found in actual practice to satisfy these conflicting requirements. In machines which have actually been constructed according to the present invention, the carriages or slides have operated successfully in automatically taking up wear and preventing inaccuracy of motion between the reciprocating parts.

Detailed construction.

Referring to the drawing in detail, Figure 1 shows a machine 10 having a hollow bed 11 with a central well 12 and raised end portions 13. Extending upwardly from the top wall 14 of the central portions 13 are integral ribs 15 having flat upper surfaces 16 and flanges 17 with abutment surfaces 18 (Fig. 3). The ribs 15 are provided with vertical bores 19 for receiving bolts 20 the heads of which engage the under surface 21 of the top wall 14.

The threaded upper ends of the bolts 20 engage threaded apertures 22 in guide rails or ways 23 and 24. By this means the guideways 23 and 24 are held firmly in the recesses formed between the surfaces 16 and 18 in the ribs 15. Upper surfaces 25 and the lateral outer surfaces 26 of the guide rails 23 and 24, are accurately machined to a high degree of flatness to engage correspondingly machined flat surfaces 27 and 28 upon the under sides 29 of carriages or slides 30. The surfaces 28 are formed upon the inside of downwardly projecting ribs or flanges 31 and 32 having a series of threaded bores 33 which receive cap screws 34 passing through apertures 35 in retaining strips 36 (Fig. 3). The ways 23 and 24 are of hardened steel.

In the right-hand rib or flange 32 the surface 28 does not directly engage the corresponding surface 26. This engagement is made by rollers 37 mounted on pins 38 secured in transverse bores 39 in hollow plungers 40. The latter are reciprocably mounted in bores 41. The plungers 40 are provided with end recesses 42 for receiving the rollers 37.

The plungers 40 are also provided with sockets 43 adapted to receive coil springs 44 seated against the walls between the recesses 41 and sockets 43. The opposite ends of the coil springs 44 engage the inner ends 45 of plugs 46 slidably mounted in the sockets 43. The plugs 46 are provided with heads 47 having transverse slots 48 adapted to receive the ends 49 of T-shaped brackets 50. The central portions of the

T-shaped brackets 50 are provided with bores 51 aligned with threaded bores 52 engaged by set screws 53 for securing the brackets 50 to the ribs 32. The slides or carriages 30 are provided with the usual flat working surfaces 54 having T-slots 55 therein for receiving hold-down bolts (not shown) by which the work to be machined is mounted upon the carriages or slide. Optionally, other tools or attachments may be mounted on the slides 30 in the same manner.

Operation

In the operation of the invention the slide or carriage 30 is placed in position upon the guide rails or ways 23 and 24 and the retaining strips 36 bolted in position to prevent the removal thereof. The plungers 40 are then inserted in the bores 41 and turned until the slots 48 of the plugs 46 are horizontal. The ends 49 of the T-shaped brackets 50 are then inserted in the slots 48 and the brackets 50 secured to the rib 32 by the set screws 53.

The slide 30 is reciprocated by any conventional mechanism (not shown). As the slide 30 reciprocates its weight maintains its surfaces 27 in engagement with the upper surfaces 25 upon the guide rails or guideways 23 and 24. At the same time, the thrust of the coil springs 44 pulls the slide 30 to the right (Fig. 3), maintaining the surface 28 on the rib 31 constantly in engagement with the surface 26 on the guide rail 23. The rollers 37 provide rolling engagement between the plungers 42 and the lateral outer surface 26 of the right-hand guide rail 24.

In this manner wear is automatically taken up and the respective guide surfaces are maintained in sliding contact during the entire operation of the machine as the slides 30 reciprocate to and fro. The precision attainable by the machine is thus greatly enhanced by this construction, and due to the fact that comparatively large surfaces are in sliding contact, the wear on the surfaces is comparatively slight.

While a specific embodiment of the invention has been described and illustrated, it will be understood that various modifications may be made within the scope of the appended claims without departing from the spirit of the invention.

What we claim is:

1. In a machine construction, a support having a plurality of elongated guides thereon, a slide mounted for sliding movement on said guides and having a portion laterally engageable with one of said guides, spaced anti-friction means for urging said slide portion into lateral engagement with said guide, yielding spring means for engaging said anti-friction means to place the same under tension, and an adjusting abutment member spanning pairs of said spaced anti-friction means and engaging said yielding means to place said anti-friction means under equal tension.

2. In a machine construction, a support having a plurality of elongated guides thereon, a slide mounted for sliding movement on said guides and having a portion laterally engageable with one of said guides, spaced anti-friction means connected to said slide for urging said slide portion into lateral engagement with said guide, yielding spring means for engaging said anti-friction means to place the same under tension, and an adjusting abutment member spanning pairs of said spaced anti-friction means and engaging said yielding means to place said anti-friction means under equal tension.

3. In a machine construction, a support hav-

ing a plurality of elongated guides thereon, a slide mounted for sliding movement on said guides and having a portion laterally engageable with one of said guides, spaced anti-friction means connected to said slide engaging another guide laterally on the opposite side from the side of lateral engagement of said first mentioned guide by said slide portion, yielding spring means for engaging said anti-friction means to place the same under tension, and a bridge member engaging at its ends with the yielding spring means of certain pairs of said anti-friction means.

4. In a machine construction, a support having a plurality of elongated guides thereon, a slide mounted for sliding movement on said guides and having a portion laterally engageable with one of said guides, anti-friction plungers connected to said slide and engaging the lateral side of another guide opposite to the side of the guide engaged by said slide portion for holding said slide in engagement with one of said guides, yielding spring means for engaging said anti-friction means to place the same under tension, and an abutment bar adjustably fastened to said slide having its ends engaging certain pairs of said yielding spring means to place said anti-friction plungers under equalized pressure.

5. In a machine construction, a support having a pair of elongated guides with lateral guide surfaces spaced at equal separations therealong, a slide mounted for sliding movement on said guides and having a portion laterally engaging one of said guide surfaces, spaced anti-friction means connected to said slide and yieldingly engaging another of said guide surfaces for yieldingly urging said slide portion into engagement with said first mentioned guide surfaces, said anti-friction means comprising plungers mounted in spaced bores formed in one of said laterally engaging slide portions having roller members rotatably mounted in the ends thereof in engagement with a corresponding guide surface, and spring members confined in said bores for yieldingly urging said rollers into engagement with said guide.

6. In a machine construction, a support having a pair of elongated guides with lateral guide surfaces spaced at equal separations therealong, a slide mounted for sliding movement on said guides and having a portion laterally engaging one of said guide surfaces, a series of bores formed in the slide in another lateral guide-engaging portion thereof, plunger members located in said spaced bores having rollers on the ends thereof for engaging the other lateral guide surface opposite to the first-mentioned lateral guide surface and coil springs confined in said bores engaging said plungers for urging the laterally engaging portion of said slide and said first guide into engagement.

7. In a machine construction, a support having a pair of elongated guides with lateral guide surfaces spaced at equal separations therealong, a slide mounted for sliding movement on said guides and having a portion laterally engaging one of said guide surfaces, a series of bores formed in another laterally engaging portion of said slide in opposed relation to said first-mentioned guide surface, a spaced yieldingly urged plunger mounted in each bore having a roller contact member thereon yieldingly engaging one of said lateral guide surfaces for urging said slide into engagement with the other lateral guide surface, coil springs confined in said bores for placing said plungers under tension, and an adjusting

member spanning certain pairs of said spaced bores having the ends thereof in engagement with said coil springs.

8. In a machine construction, a support having a pair of elongated guide members each having an upper guide surface and a lateral guide surface, a slide mounted for sliding movement upon said upper guide surface and having a portion engageable with one of said lateral guide surfaces, a series of bores formed in the slide in another lateral guide-engaging portion thereof, plunger members located in said spaced bores having rollers on the ends thereof for engaging the other lateral guide surface for urging said first-mentioned slide portion into engagement with said first-mentioned lateral guide surface, coil springs confined in said bores for placing said plungers under tension, plunger members engaging the other ends of the coil springs and telescoped with the first-mentioned plunger member, and an adjusting bar spanning certain parts of said second-mentioned plunger member to maintain the first-mentioned plungers under tension.

9. In a machine construction, a support having a pair of elongated guide members each having an upper guide surface and a lateral guide surface, a slide mounted for sliding movement upon said upper guide surface and having a portion engageable with one of said lateral guide surfaces, 25

5 a plurality of spaced yieldingly-urged spaced plungers mounted on said slide, rollers carried by each plunger, and yieldingly engaging the other lateral guide surface for urging said slide portion into engagement with said first-mentioned lateral guide surface and a bridge member for equally tensioning the plungers and rollers.

10 10 In a machine construction, a support having a pair of elongated guide members each having an upper guide surface and a lateral guide surface, a slide mounted for sliding movement upon said upper guide surface and having a portion engageable with one of said lateral guide surfaces, 15 a series of spaced bores formed in the slide in another lateral guide-engaging portion thereof in opposed relation to the first-mentioned guide engaging portion, plungers mounted in each of said bores, rollers carried by each plunger in engagement with the other lateral guide surface, coil springs mounted in recesses in said plungers, plunger pins extending into said recess engaging said coil springs for urging said slide portion into engagement with, said first-mentioned lateral guide surface and abutment bars spanning certain pairs of said plunger pins connected to said slide, said abutment bars being provided with projections for reception in depressions in the outer ends of said plunger pins.
